US00D937407S

(12) **United States Design Patent** (10) Patent No.: **US D937,407 S**
(45) Date of Patent: **** Nov. 30, 2021**

(54) **NASAL CANNULA**

(71) Applicant: **Fisher & Paykel Healthcare Limited**,
Auckland (NZ)

(72) Inventors: **Daniel Charles Wilson**, Auckland
(NZ); **Chelsea Erin Johnson**, Auckland
(NZ); **Leon Tyler Stanley**, Auckland
(NZ); **Michael Paul Ronayne**,
Auckland (NZ); **Anna Rose Northey**,
Auckland (NZ)

(73) Assignee: **Fisher & Paykel Healthcare Limited**,
Auckland (NZ)

(**) Term: **15 Years**

(21) Appl. No.: **29/745,861**

(22) Filed: **Aug. 10, 2020**

Related U.S. Application Data

(60) Division of application No. 29/706,031, filed on Sep.
17, 2019, now Pat. No. Des. 893,015, which is a
continuation of application No. 29/677,686, filed on
Jan. 23, 2019, now Pat. No. Des. 865,943, which is a
division of application No. 29/627,025, filed on Nov.
21, 2017, now Pat. No. Des. 849,243.

(57) **CLAIM**

The ornamental design for a nasal cannula, as shown and
described.

DESCRIPTION

FIG. 1 is a top, front and right side perspective view of a
nasal cannula embodying our new design.

FIG. 2 is a top, rear and right side perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof; and,

FIG. 8 is a rear view thereof.

Dash-dash broken lines are used to illustrate portions of the
nasal cannula which form no part of the claimed design.

1 Claim, 4 Drawing Sheets
